SHOEHORN OR THE LIKE

Thure Jaderborg, Jr., Lindsborg, Kans.

Application June 3, 1953, Serial No. 25,301

Term of patent 7 years

(Cl. D86—10)

To all whom it may concern:

Be it known that I, Thure Jaderborg, Jr., a citizen of the United States, residing at Lindsborg, in the county of McPherson and State of Kansas, have invented a new, original, and ornamental Design for a Shoehorn or the like, of which the following is a specification, reference being had to the accompanying drawing, forming a part thereof.

In the drawing:

Figure 1 is a front elevational view of the shoehorn or the like, showing my new design;

Figure 2 is a side elevational view of the shoehorn or the like, looking from right to left of Figure 1;

Figure 3 is a perspective view thereof as the shoe horn or the like appears looking from the right of Figure 2, and

Figure 4 is a cross-sectional view thereof taken substantially along a plane as indicated by the line 4—4 of Figure 2.

I claim:

The ornamental design for a shoehorn or the like, substantially as shown.

THURE JADERBORG, JR.
